[57] CLAIM

The ornamental design for a wrist watch, as shown and described.

DESCRIPTION

FIG. 1 is a top plan view of wrist watch showing my new design;

FIG. 2 is a right side elevational view thereof, the left side being a mirror image thereto without the crown.

FIG. 3 is a bottom plan view thereof;

FIG. 4 is an end elevational view thereof; the opposite end being a mirror image thereto.
